UNITED STATES PATENT OFFICE.

CHAUNCEY H. CASTLE, OF QUINCY, ILLINOIS, ASSIGNOR TO COMSTOCK,
CASTLE & CO., OF SAME PLACE.

DESIGN FOR A HEATING-STOVE.

Specification forming part of Design No. 5,901, dated June 4, 1872.

Specification describing a new and original Design for a Stove-Front, invented by CHAUNCEY H. CASTLE, of Quincy, in the county of Adams and State of Illinois.

The photographic illustration fully represents my new design.

This invention relates to a new ornamental design for the face-plate and doors of stoves, more particularly of tod-stoves of the form shown in the photograph.

The door has an oval bas-relief shield in the middle, surrounded by ornamental scroll, as shown. The face-plate of the stove has around the door a continuous border of undulating foliage. The same design appears at the back end of the stove, where, however, the door is only in imitation, and not hinged.

The invention also relates to the decoration of the urn-supports on the middle of the stove, said urn-supports being of rectangular outline, and provided at the sides with spear-shaped, scalloped, and other ornaments, as shown.

I claim as my invention—

1. The design for the face-plate of a tod-stove, as shown.
2. The design for the door of a tod-stove, as shown.
3. The design for the urn-supports of a tod-stove, as shown.

CHAUNCEY H. CASTLE.
